CLAIM

The ornamental design for a bottle lifter, as shown and
described.

DESCRIPTION

FIG. 1 is a perspective view of a bottle lifter showing
my new design;
FIG. 2 is a top plan view thereof;
FIG. 3 is a front elevational view thereof, the rear ele-
vational view being a mirror image;
FIG. 4 is a right side elevational view thereof;
FIG. 5 is a left side elevational view thereof;
FIG. 6 is a bottom plan view thereof;
FIG. 7 is a perspective view of an alternative embodi-
ment of the bottle lifter of FIG. 1;
FIG. 8 is a top plan view thereof;
FIG. 9 is a front elevational view thereof, the rear ele-
vational view being a mirror image;
FIG. 10 is a right side elevational view thereof;
FIG. 11 is a left side elevational view thereof; and,
FIG. 12 is a bottom plan view thereof.
